L. S. HINCKLEY.
LACING TERMINAL.
APPLICATION FILED APR. 30, 1919.

1,314,805.

Patented Sept. 2, 1919.

INVENTOR:

Livingston S. Hinckley,

BY *Russell M. Everett,* ATTORNEY.

UNITED STATES PATENT OFFICE.

LIVINGSTON S. HINCKLEY, OF NEWARK, NEW JERSEY.

LACING-TERMINAL.

1,314,805.

Specification of Letters Patent.

Patented Sept. 2, 1919.

Application filed April 30, 1919. Serial No. 293,649.

To all whom it may concern:

Be it known that I, LIVINGSTON S. HINCKLEY, a citizen of the United States, and a resident of Newark, in the county of Essex and State of New Jersey, have invented new and useful Improvements in Lacing-Terminals, of which the following is a specification.

This invention relates generally to that 10 class of inventions known as lacing terminals, and more particularly to such devices the purpose of which is to prevent the bow knot of the lacing from coming inadvertently untied.

15 The objects of the invention are to provide a device of this character by which tension may be maintained upon the lacing; to thus keep the knot or bow drawn tight and thereby prevent its untying; to avoid 20 concealing any part of the knot, and on the other hand to conceal the device by the knot; to secure simplicity of construction and operation, and to obtain other advantages and results as may be brought out in 25 the following description.

Referring to the accompanying drawing, in which like numerals of reference indicate the same parts throughout the several views,

Figure 1 is a front view of a portion of a 30 shoe with my invention in place and showing the lacing being applied thereto;

Fig. 2 is a similar view showing the bow tied;

Fig. 3 is a front view of the invention; 35 Figs. 4 and 5 are sectional views on lines 4-4 and 5-5 respectively of Fig. 3;

Fig. 6 is a front view of a modified structure, and

Fig. 7 is a sectional view on line 7-7 of 40 Fig. 5.

In the specific embodiment of the invention illustrated in said drawing, the reference numeral 1 indicates my improved lacing terminal or knot tightener which 45 comprises preferably a single piece of sheet metal having a requisite degree of resiliency to meet the requirements for which the device is made. The device provides a body portion 1 in the example shown, which is 50 slightly curved to adapt it to fit upon the wearer's person, and sufficient in size to not be uncomfortable when held by pressure in place. While shown substantially elliptical in shape, it may be other shapes without departing from the spirit of the invention. 55 A resilient tongue 2 is provided, bent pref-

erably from one edge of the body portion and returned to extend in the same general direction as the body portion, so that in use the tongue will be positioned in front 60 of the body portion. Except at its end 3 where integral with said body portion, the tongue is spaced therefrom, and its resiliency resists pressure tending to swing it 65 toward the body portion.

In use the device is placed behind the bow or knot 4 by which a shoe lace 5 is tied, with the bow upon or crossing the tongue 2 and tied sufficiently tight to depress the tongue, which will then, by virtue of its resiliency, 70 exert a tension upon the bow and thus keep it from coming untied. It is to be particularly noted that the device does not pass over any part of the knot to obscure it or detract from its attractiveness or neat 75 appearance, but the knot, on the contrary, conceals to a great extent the device from view.

In order to prevent the knot from slipping off of the tongue, suitable projections are 80 provided, the same being shown in the structure of Figs. 1 to 5 as ears or flanges 6 outstanding from the longitudinal edges of the tongue, it being intended in this structure that the shoe lacing extend longitudinally 85 upon the tongue. In Figs. 6 and 7, however, it is intended that the shoe lacing extend transversely of the tongue, and the projections in this instance are formed by striking up a pair of spaced ridges 8 in the tongue 90 providing a hollow 9 therebetween for the reception of the lacing.

For the purpose of securing the device against shifting from place or becoming lost, the laces may be passed through holes 10, 10 95 in the body portion, as in the modified structure of Figs. 6 and 7, or may one be passed through a hole 11 and the other engaged in a notch 12 as shown in the first five figures. It may be noted that hole 11 is in the body 100 portion 1 of the device beneath the free end of the tongue, and that the tongue is notched thereabove, as at 13, to receive the shoe lace. At the other end of the tongue, the notch 12 is in both tongue and body portion. One 105 free end of the shoe laces passes out through hole 11 and into notch 13 in the end of the tongue, the other free end of the shoe lace engaging in the notch 12 of the tongue and body, the said ends of the lace extended 110 along the tongue and tied tightly, thereby depressing the tongue and maintaining the

tied shoe lace under tension. While in Figs. 1 to 5 the shoe lace is passed longitudinally of the tongue, in Figs. 6 and 7 it is intended to be passed transversely of the tongue, but 5 functions the same in both instances in exerting tension upon the tied ends of the shoe lace.

While I have shown my invention applied to the lacing of a shoe, it will be understood 10 that it can be employed for any lacing whatever, without departing from the spirit and scope of the invention, and I do not wish to be understood as restricting myself except as required by the following claims when 15 construed in the light of the prior art.

Having thus described the invention, what I claim is:

1. A lacing terminal comprising a body portion adapted to be inserted beneath a knot in a lace, and means interposed between said body portion and the knot for maintaining a tension on said knot to prevent accidental untying thereof.
2. A device of the character described comprising a body portion, and a resilient tongue normally spaced from said body portion, said body portion and tongue being adapted to be inserted beneath a knot in a lace to maintain tension against the same to 30 prevent accidental untying.
3. A device of the character described comprising a body portion, and a resilient member carried thereby and normally resisting pressure toward said body portion, said 35 body portion and resilient member being adapted to be inserted beneath a knot in a

lace whereby the resilient member maintains a tension upon said knot to prevent accidental untying thereof.

4. A lacing terminal comprising a body 40 portion adapted to be threaded upon the ends of a lace, and a resilient member carried by said body portion and normally resisting pressure toward said body portion, the said resilient member being constructed 45 to have a knot tied thereover and to maintain tension in said knot to prevent accidental untying thereof.

5. A lacing terminal comprising a body portion of spring sheet material, an integral 50 spring tongue returned over said body portion and resisting pressure toward the body portion, said body portion and tongue being adapted to be inserted beneath a knot in a lace so that the tongue maintains a tension 55 upon said knot to prevent accidental untying thereof.

6. A lacing terminal comprising a body portion of spring sheet material, said body portion being provided with openings for 60 threading the same upon the ends of a lace and an integral spring tongue returned over said body portion and resisting pressure toward the same, said tongue being interposed between the knot and the body portion 65 when the lace is tied so as to maintain a tension upon the knot to prevent accidental untying thereof, and said tongue being formed with means for holding the lace on said tongue.

LIVINGSTON S. HINCKLEY.
